UNITED STATES PATENT OFFICE.

GEORGE W. SWARTZ, OF FLORENCE, ALABAMA.

ELECTRIC SIGNAL.

SPECIFICATION forming part of Letters Patent No. 500,041, dated June 20, 1893.

Application filed October 31, 1892. Serial No. 450,533. (No model.)

To all whom it may concern:

Be it known that I, GEORGE W. SWARTZ, a citizen of the United States, residing at Florence, in the county of Lauderdale and State of Alabama, have invented certain new and useful Improvements in Electric Signals, of which the following is a specification, reference being had therein to the accompanying drawings.

This invention relates to certain new and useful improvements in railway signals to be used on trunk line railroads or electric roads, and it has for its objects among others to provide a cheap, practical and efficient system of signals to be located along the line of roads at stations and switches to enable the employés to know when a switch is misplaced or a train has left a station and is advancing toward another station; a signal or alarm is automatically given to the agent or watchman so that any train coming in the opposite direction may be signaled and detained until the arrival of the train at the station. In like manner when a switch is misplaced from the main track the employés are notified.

The invention has for a further object the location of trains when running in sections one following another; when the first section has passed the contact or circuit closer the alarm is sounded or a signal given at the next station to notify the agent or watchman that the train has passed said station. When the train has passed the circuit closer is released and the circuit broken and the alarm stops but when the next section passes the circuit is again closed and the alarm sounds again, and the agent or watchman having noted the first alarm by his watch and noting the time of the second alarm, is enabled to know when the trains are running too close together, and can notify the section of danger or rear end collision and by the danger signals which are arranged to be shown at the track or located in a conspicuous place where passing trains can see them and note the danger.

The invention as above outlined is capable of application in various forms and while some of those forms are illustrated and will now be described the invention is not restricted thereto in the matter of details of construction.

Other objects and advantages of the inven-

tion will hereinafter appear and the novel features thereof will be specifically defined by the appended claims.

The invention is clearly illustrated in the accompanying drawings, which, with the letters of reference marked thereon, form a part of this specification, and in which—

Figure 1 is a plan of a section of track of a line equipped with my improvements. Fig. 2 is a diagrammatic view with parts in vertical section showing means for operating a drop slide for a light. Fig. 3 is a sectional view showing the circuit closing device. Fig. 4 is a like view showing the circuit closer adapted for a switch rail. Fig. 5 is a plan at the switch. Fig. 6 is a detail of the shoe which is carried by the train for operating the circuit closer.

Like letters of reference indicate like parts throughout the several views.

Referring now to the details of the drawings by letter, A designates the main line tracks of known construction, and as seen in Fig. 5 A' is a siding and A² the switch rails, the latter being designed to be operated in any suitable way and the mechanism for actuating the same is therefore not shown.

B are wires connecting one station with another and these wires can be run in any desired manner, along the tracks and fastened to the ties by suitable insulators, or upon poles, strung upon which are the wires, and the poles arranged as may be most convenient; in Fig. 1 the wires are shown as strung upon poles B', but either manner may be adopted according to circumstances or as occasion may require.

D is a circuit closer supported upon a tie in any suitable manner, preferably upon the inside or between the rails, and insulated therefrom by suitable insulation. This circuit closer comprises a suitable casing of required shape and dimensions, and in its preferred form is of the construction shown in detail in Fig. 4, there being two contact plates D' and D² the former of which is connected by suitable wire d' with the ground and the other connected by suitable wire d² with a battery E. These contacts are normally separated and the circuit is broken. The circuit is closed in the following manner: Projecting laterally from the casing of the circuit closer

and mounted to slide through an opening therein is a rod E' the outer end of which is tapered or beveled as shown and normally held outward by the action of a spring E² surrounding the rod within the case, being held between the inner wall of the case and a flange, collar or other suitable stop e on the inner end of the rod as seen in Fig. 4. Normally this rod is held outward as seen in Fig. 4 and out of contact with the plate D² which is consequently held from the plate D' and the circuit is broken, but when a train comes along on the track a shoe or some analogous contrivance upon the locomotive or other part of the train comes in contact with the outer end of the rod E' and forces it inward against the plate D² and forces the same against the plate D' completing the circuit; in the circuit is included a light F and an alarm at the one station and an alarm at the next station. In Fig. 1 supposing the train to be going in the direction of the arrow there shown, when the rod E' is pushed in the circuit is completed and a slide is automatically dropped disclosing a red light; this is accomplished in the following manner:

G is a casing within which is arranged an electro magnet, or it may be more than one, and upon a suitable support a red light G' which at night is kept lighted.

G² is a slide arranged to slide vertically in suitable guides and normally held up so as to hide the light by the arm H of a bell crank lever H' pivoted at h and having the free end of said arm beveled upon the under face as seen best in detail at the bottom of Fig. 2 and its other arm having a projection h², the slide having at its upper end a lateral projection engaged by the said arm H as seen in Fig. 2 by full lines; the arm H² of this lever being normally engaged with the armature I of the magnet G³ which latter is connected with the battery E by suitable wire g'. The other pole of the magnet is connected with the ground by suitable wire g² and the armature is pivoted as at g³.

I' is a contact held within the case and connected by wire i with the alarm I² which is connected with the ground by suitable wire i' all as shown in Fig. 2. Now as the circuit is closed the armature is attracted by its magnet and the end thereof is drawn away from the projection of the arm H² of the bell crank lever when the weight of the slide causes it to drop and the arm H² of the bell crank lever is caused to engage the contact I' and thus complete the circuit through the alarm I² which may be arranged in any suitable place; thus the light is exposed and the alarm given at the same time. The alarm is preferably arranged at the next station as seen in Fig. 1.

In Fig. 6 I have shown a suitable form of shoe for actuating the rod E'; it is carried by a suitable rod j working in guides j' on a plate J' which is designed to be secured to

the locomotive in any suitable manner, the shoe J being rounded in opposite directions so as to operate in the movement of the train in either direction, and is arranged to slide in a horizontal direction when used in connection with the form of contact closer above described. A spring J² is employed for normally holding the shoe outward to its work.

In single line roads I arrange the parts above described upon each side of the track as shown in Fig. 1, so as to be operated by a train moving in either direction.

In Fig. 3 I have illustrated a modified form of contact closer, working however on the same principle and which may be substituted for the one just described. In this form one of the contact plates is in the form of a substantially U-shaped spring plate K suitably secured upon the base of the casing and insulated therefrom by suitable insulation k and being connected with the main line by wire k' as shown in said Fig. 3, the other contact being formed by the sliding rod E' spring pressed by spring E² and connected with the ground by means of wire k² all as shown in Fig. 3. The operation is substantially the same as in the form above described; the rod is normally held away from the plate K by the spring but when engaged by the shoe on the train it is forced inward, contacting with the plate K and completing the circuit when the same result occurs as before.

Modifications in detail may be resorted to without departing from the spirit of the invention or sacrificing any of its advantages.

What I claim as new is—

1. The combination with a signal and a slide for normally holding the same, of a pivoted lever having one arm engaging said slide, an electro magnet, its armature arranged to prevent movement of said lever until the circuit is closed, and a contact for engaging the lever when the circuit is closed, as set forth.

2. The combination with the slide having a projection at the end, of a pivoted bell crank lever having one end beveled to engage said projection, an armature and magnet for normally holding the slide in its elevated position, and a contact against which said lever is designed to engage, as and for the purpose specified.

3. The combination with the slide and the bell crank lever for holding the same pivoted at its elbow and one arm formed with a projection, of a magnet, its armature pivoted and arranged to engage said projection, and a contact point for engaging said lever when the latter is disengaged from the armature, as set forth.

In testimony whereof I affix my signature in presence of two witnesses.

GEORGE W. SWARTZ.
